(57) **CLAIM**

The ornamental design for a carrier for containers, as shown and described.

DESCRIPTION

FIG. 1 is a perspective view of a carrier for containers showing our new design.

FIG. 2 is a left elevation view of the carrier for containers of FIG. 1, the right elevation view is a mirror image.

FIG. 3 is a front elevation view of the carrier for containers of FIG. 1, the rear elevation view is a mirror image.

FIG. 4 is a top plan view of the carrier for containers of FIG. 1.

FIG. 5 is a bottom plan view of the carrier for containers of FIG. 1; and,

FIG. 6 is a plan view of the carrier for containers of FIG. 1 shown in an unfolded configuration.

The broken lines are shown for the purpose of illustrating both parts of the carrier for containers as well as environmental subject matter of exemplary containers. None of the broken lines form part of the claimed design.
